UNITED STATES PATENT OFFICE.

PHILIP SCHNEIDER, OF SHIPMAN, ILLINOIS.

LINE-GUIDE FOR HARNESS.

SPECIFICATION forming part of Letters Patent No. 249,105, dated November 1, 1881.

Application filed July 27, 1881. (No model.)

To all whom it may concern:

Be it known that I, PHILIP SCHNEIDER, of Shipman, in the county of Macoupin and State of Illinois, have invented certain new and useful Improvements in Line-Guides for Harness; and I do hereby declare the following to be a full, clear, and exact description of the same, reference being had to the accompanying drawings, forming a part of this specification, in 10 which—

Figure 1 is a perspective view of one of the guides. Fig. 2 is a view showing the application of the guides to a pair of hames.

Similar letters of reference in the several figures denote the same parts.

My invention has for its object to provide improved guides for the driving-lines of a harness which will permit of the ready insertion and removal of the lines, and through which 20 the lines can run with but little friction.

To this end the invention consists in guides constructed as I will now proceed to describe.

In the drawings, A represents a metal shank adapted to be secured to the hames or other part 25 of the harness; B B, a pair of side bars secured to the inner bars, B' B', which are in turn secured to the said shank rigidly, or, as shown, by a pivot, b; C, a friction-roller or sleeve loosely mounted between the side bars, B B, upon a 30 bolt or rivet, c; and D, a second and outer friction roller or sleeve, also loosely mounted between the said side bars, near the outer ends of the same, upon the shank of a screw-bolt, E, which extends through perforations in the ends 35 of said side bars, and is adapted to be screwed in and out by means of the thumb-piece e on its end. The sleeve C has heads or flanges c' c' at its ends, also loosely mounted on the bolt or rivet c.

The lines are applied by unscrewing the 40 screw-bolt E and removing the outer friction-sleeve, D, then inserting the lines against the sleeve C and between the heads c' c', and finally replacing the sleeve D and screw-bolt E, as will be readily understood. The lines when 45 in place, it will be seen, are bounded on all sides by revolving surfaces—that is to say, by the friction-sleeves at their sides and the revolving heads c' c' at their upper and lower edges—and the friction is therefore reduced to 50 a minimum. Besides the lines are held always in proper position—*i. e.*, on edge—and are thereby prevented from twisting.

The devices are very simple and can be made at slight cost.

The flanges or heads c' c' may be formed solid with the sleeve C, if preferred, and the bars B' B' may be hinged to the shank A or not, though I rather prefer that they should be.

Having thus described my invention, I claim 60 as new—

1. In line-guides, the combination, with the side bars, the inner bars, and a shank to which the latter are connected, of the inner friction-sleeve and the outer removable friction-sleeve, 65 both mounted in the side bars, substantially as described.

2. In line-guides, the combination of the shank, the side bars, the inner bars, the inner friction-sleeve, the loose heads, and the outer 70 friction-sleeve, substantially as described.

PHILIP SCHNEIDER.
